UNITED STATES PATENT OFFICE.

WILLIAM A. GEIGER, OF CHICAGO, ILLINOIS, ASSIGNOR TO WILLIAM H. MINER, OF CHAZY, NEW YORK.

HAND-BRAKE FOR RAILWAY-CARS.

1,378,852.

Specification of Letters Patent.

Patented May 24, 1921.

Application filed February 4, 1920. Serial No. 356,258.

To all whom it may concern:

Be it known that I, WILLIAM A. GEIGER, a citizen of United States, residing at Chicago, in the county of Cook and State of Illinois, have invented a certain new and useful Improvement in Hand-Brakes for Railway-Cars, of which the following is a full, clear, concise, and exact description, reference being had to the accompanying drawings, forming a part of this specification.

This invention relates to improvements in hand brakes for railway cars.

The object of the invention is to provide a simple, practical and substantially weatherproof hand brake of the vertical staff type for railway cars and wherein is employed an operating handle adapted to assume an inoperative position, under the influence of gravity.

In the drawing forming a part of this specification, Figure 1 is a vertical part sectional view, part elevational view of a portion of a car showing my improvements in connection therewith. The end wall of the car and the housing are shown in section, the other parts being in elevation. Fig. 2 is a horizontal sectional view taken substantially on the line 2—2 of Fig. 1. Fig. 3 is a vertical sectional view taken substantially on the line 3—3 of Fig. 1, the operating handle being shown in section in Fig. 3 on the assumption that the operating handle is in its horizontal operative position. Fig. 4 is a detail sectional view showing another arrangement for mounting the operating handle and pawl.

In said drawing, 10 denotes the end wall of a car, such as a gondola, 11 the usual platform or step for the brakeman, and 12 the usual vertical brake staff. As is well understood in the art, the vertical brake staff usually has a drum at the bottom thereof around which the chain leading to the brake beam winds. As is also customary, the brake staff is provided with a ratchet wheel 13 adjacent the platform 11 and with which is adapted to coöperate a foot-controlled locking dog (not shown).

In carrying out my invention, I provide a suitable bearing bracket 14 near the upper end of the staff 12, said bracket 14 being secured in any suitable manner to the wall of the car and provided with a bearing for

the staff. Above the bearing bracket 14, the staff 12 is provided with a squared section 15 on which is mounted a ratchet wheel 16. Above the ratchet wheel 16 the staff 12 is provided with a cylindrical section of reduced diameter as indicated at 17.

Coöperable with the ratchet wheel 16 is a pawl 18 which is preferably formed integrally with an operating handle 19. Said combined pawl and handle 19 is pivotally mounted on a pivot pin 20 carried by a supporting member 21, the latter in turn being pivotally mounted about a horizontal axis on the two elements designated by the references A and B, the latter being oscillatably mounted on the staff 12, as hereinafter explained. Also mounted on the staff 12 and adapted to form a suitable weather-protecting shield for the ratchet wheel and associated parts, is a housing 22, the same having a bearing as 23 on the staff 12 so as to permit the housing to oscillate. All of the parts are held in assembled relation on the staff by any suitable means such as the washer 24 and nut 25, the upper end of the staff being preferably upset over the nut as indicated at 26.

The members A and B are of U-shape or forked construction and are of substantially similar construction although not identical. The member A has an upper arm 27 having a suitable bore to fit on the section 17 of the staff and a lower arm 28 also suitably bored to fit the main portion of the staff. The element B is similarly provided with an upper horizontally extending arm 29 bored to receive the section 17 of the staff and a lower arm 30 bored to accommodate the main portion of the staff.

As clearly evident from an inspection of Fig. 1, the arms of the members A and B are arranged to straddle the ratchet wheel 16 and the upper and lower arms of the member A are above the upper and lower arms, respectively, of the element B. The elements A and B are extended beyond the ratchet wheel 16 and in such manner as to accommodate the hanger 21 therebetween as shown in Figs. 2 and 3. The hanger 21 is preferably provided with integrally formed lugs 31—31 which are accommodated in corresponding openings in the elements A and B, said lugs being riveted over at their ends as indi-

cated at 32 and thereby forming pivotal support for the member 21 and simultaneously holding the elements A and B and hanger 21 in proper assembled relation.

5 The hanger 21 is formed with an opening 33 therein to accommodate the handle 19, the opening 33 being suitably beveled on opposite sides of the pivot 20 as indicated at 34—34 in Fig. 2, to permit the oscillatory movements of the combined pawl and handle 18—19. It will be noted that the axes of the pivots for the hanger 21 and of the combined operating pawl and handle are at right angles to each other. The pawl 18, proper, is preferably offset or arranged at an angle with respect to the handle 19, as indicated in Fig. 2 and said pawl will also preferably have a lug 35 which will coöperate with a vertical wall 36 of the housing to 10 limit the swinging movements of the handle 19 toward the staff, when the handle is in inoperative condition.

As will be understood from the preceding description in connection with the drawing, 25 the operating handle 19 and pawl 18 will automatically assume inoperative positions under the influence of gravity. When it is desired to tighten the brake, the brakeman lifts the handle 19 to the horizontal position 30 indicated by dotted lines in Fig. 1 which will bring the pawl 18 into the plane of the ratchet wheel 16 and permit of coöperating ratcheting action with respect thereto, as the brakeman oscillates the handle 19 backward and forward. The brake chain or 35 staff 12 is held against reverse rotation by the ratchet wheel 13 and foot-controlled locking dog (not shown).

With my construction, the parts may be 40 readily assembled on a bracket staff such as are now most commonly used and a satisfactory housing for all of the parts is obtained without any appreciable additional expense and in this connection it will be noted 45 that the housing will oscillate in accordance with the oscillation of the elements A and B which fit more or less snugly within the housing, as indicated by the cross sectioned outline of the housing in Fig. 2.

50 In the construction shown in Fig. 4, the hanger 121 for the operating handle is made of substantially U-shape without any integral pivot forming lugs. The pivotal support for the hanger 121 in the elements 55 A' and B' is obtained by a separate rivet or pin 131 headed at its ends as indicated at 132. With this construction, the pivot for the operating handle 119 may be obtained by an integral lug 120 on the hanger 121. 60 In this construction, the handle 119 will be held in proper position with respect to the hanger 121 by the rivet pin 131 which passes over the top of the lug 120. The hanger 121 is of somewhat simpler form than that 65 shown in Figs. 1, 2 and 3.

I claim:

1. In a brake of the vertical staff type for railway cars, the combination with a vertical staff having a ratchet wheel rotatable in unison therewith, of a pawl coöperable 70 with said ratchet wheel, and means for supporting said pawl to permit its bodily oscillation in a horizontal plane with respect to said staff, said means including two elements each independently journaled on said 75 staff, and a support for said pawl carried by said two elements.

2. In a hand brake of the vertical staff type for railway cars, the combination with a vertical staff having a ratchet wheel near 80 the top thereof rotatable in unison therewith, of a pawl coöperable with said ratchet wheel, two elements separately journaled on said staff, a support carried by said elements and on which said pawl is oscillatably 85 mounted, and a housing oscillatably mounted on said staff, said housing fitting over the ratchet wheel and portions of said elements and oscillatable in unison with the latter.

3. In a hand brake of the vertical staff 90 type for railway cars, the combination with a vertical staff having a ratchet wheel near the top thereof rotatable in unison therewith, of two forked elements straddling 95 said ratchet wheel and independently oscillatably mounted on the staff, a hanger pivotally mounted on said elements and in line with said ratchet wheel, and a combined pawl and operating handle pivotally mounted 100 on said hanger about an axis which extends vertically when the pawl and handle are in operative position.

4. In a hand brake of the vertical staff type for railway cars, the combination with a vertical staff having a ratchet wheel near 105 the top thereof rotatable in unison therewith, of two U-shaped elements each having the arms thereof journaled on the staff, said elements extending outward beyond the periphery of the ratchet wheel, a hanger pivotally mounted on said elements to swing about a horizontal axis and a combined pawl and operating handle pivotally mounted on 110 said hanger about an axis which extends vertically when the hanger is in vertical position and with the operating handle in a horizontal position.

5. In a hand brake of the vertical staff type for railway cars, the combination with a vertical staff having a ratchet wheel near 115 the top thereof rotatable in unison therewith, of two U-shaped elements each having the arms thereof journaled on the staff, said elements extending outward beyond the periphery of the ratchet wheel, a hanger pivotally mounted on said elements to swing about a horizontal axis, a combined pawl and operating handle pivotally mounted on 120 said hanger about an axis which extends vertically when the hanger is in vertical position and with the operating handle in a horizontal position.

125

130

tion and with the operating handle in a horizontal position, and a housing oscillatably mounted on the staff at the top thereof, said housing fitting over the ratchet wheel and 5 said elements, the housing being oscillatable in conjunction with the latter with respect to the staff.

In witness that I claim the foregoing I have hereunto subscribed my name this 30th day of January 1920.

WILLIAM A. GEIGER.
